JOHN R. McDERMET, OF JEANNETTE, PENNSYLVANIA, ASSIGNOR TO ELLIOTT COMPANY, OF JEANNETTE, PENNSYLVANIA, A CORPORATION OF PENNSYLVANIA

METHOD AND APPARATUS FOR DEAERATING

Application filed January 28, 1931. Serial No. 511,874.

The present invention relates broadly to the art of heat exchanging, and more particularly to this art as applicable to the deaeration of water.

5 In the deaeration process, there are certain conditions the obtaining and maintaining of which are essential to the production of commercial results. In accordance with certain known processes, it is customary to provide 10 distinct stages or treatment zones through which the water passes progressively.

In apparatus of such character, the water is brought into contact with heating steam in one of the zones, which for purposes of 15 convenience may be termed the heating stage, and is raised to a temperature as high as it is possible to raise it in the presence of the air present in the steam originally supplied and released from the water during the heating 20 thereof. It is well recognized that this temperature differential between the full steam temperature and the water is such that there is a considerable air content left in the water. This air content can be removed only by subjecting the water to treatment in the second 25 stage in which there is maintained a more nearly pure steam atmosphere. In such an atmosphere the remaining air in the water passes therefrom into the atmosphere to such 30 an extent that the air in the water and the air in the atmosphere come into pressure equilibrium. Such second stage may therefore be termed a pressure stage of water treatment.

35 While the distinct two stage or zone treatment possesses certain desirable advantages from the standpoint of operation, it is open to possible criticism from the standpoint of initial cost.

40 I have found that it is possible to obtain the deaeration results required commercially by subjecting the water progressively to the action of steam in successive strata, whereby the temperature of the water is progressively 45 raised, provided such strata are subjected to a steam withdrawal action of such character that the stratum having the least temperature rise is subjected to the most effective withdrawal.

50 By way of general introduction, it may be

assumed that in an apparatus of the tray type the water is to pass successively over each of the desired number of trays, six of such trays being assumed by way of example. These trays will obviously define horizontally 55 superimposed zones or strata through which the water progressively passes in going from one tray to the other. If each of the strata is supplied with heating steam, the temperature rise in the first stratum will be greatest, 60 since in this zone the coldest water comes into contact with the steam. Thereafter, the temperature will be a more gradual one which may be considered as generally comparable to the time element together with the rate of air 65 removal. Thus in the last zone or stratum of treatment the temperature rise will be of a minimum amount, and except for affording a possibility of pressure equilibrium of the 70 character referred to, almost negligible.

Since, however, pressure equilibrium involves the release of air and therefore air contamination of the steam atmosphere, it is essential that the steam atmosphere be continuously renewed. Since the temperature 75 rise, as before stated, is almost negligible in the last zone of treatment, the tendency toward an induced flow of steam into such zone is likewise almost negligible. Under normal conditions of operation such zone 80 would tend to become stagnated and therefore useless. It is one of the objects of the present invention to provide a method and apparatus characterized by the possibility of effecting continuous renewal of the steam at 85mosphere in such zone by insuring the continuous passage of steam into such zone and its continuous removal therefrom.

Since, as before pointed out, the temperature rise in the successive strata is a decreasing one, the steam flow induced into such strata is likewise a decreasing one. It is further one of the objects of the invention to provide a method and apparatus characterized by the possibility of modifying the 90 normal steam flow into such strata and establishing and maintaining a condition such that the tendency toward steam flow into such strata is progressively increased in contravention of the natural logarithmic law. 95

In accordance with the present invention such a result may be accomplished by making provision for more effective venting of the strata progressively in the direction of the

6 water flow whereby the last stratum is characterized by a greater potential venting capacity than the stratum preceding it, the capacity preferably decreasing gradually in a direction counter to the water flow.

10 Since venting of the character herein contemplated represents appreciable steam removal and therefore the continuous withdrawal of large heat quantities from the apparatus, I preferably utilize a withdrawing 15 or steam flow inducing means of such nature that it is possible to continuously recover the heat of withdrawn vapors and gases and impart the same to the water to be deaerated.

20 A vent condenser is characterized by the ability to withdraw vapors and gases and induce the desired flow conditions, and is further characterized by the ability of transferring a large portion of the heat of the withdrawn mixture to the condensing medium. In commercial practice therefore, it is desirable in most cases to utilize a vent condenser for this purpose, although the utility of the invention is not thus limited.

30 In the accompanying drawings there are shown by way of illustration only, more or less diagrammatically, certain preferred embodiments of the present invention. In the drawings:

35 Figure 1 is a diagrammatic view illustrating by a curve the relationship between the direction of water flow and the venting capacity;

40 Figure 2 is a view similar to Figure 1, representing diagrammatically the relationship between air quantity and temperature rise with respect to direction of water flow;

45 Figure 3 is a diagrammatic view illustrating one form of apparatus producing the results graphically illustrated in Figures 1 and 2; and

Figure 4 is a view similar to Figure 3 illustrating another embodiment of the invention.

50 In carrying out the present invention, there may be provided apparatus of a number of different types so constructed as to give the conditions of operation desired. In Figure 3, I have illustrated one form of apparatus as comprising a shell or container 2 having an inlet 3 for the water to be deaerated and 55 an outlet 4 effective for conveying deaerated water to the desired point of use.

60 Located within the container 2 is a series of trays substantially horizontally disposed and extending transversely of the container in cooperative relation to a steam inlet 5. In the illustrated embodiment I have shown six 65 of such trays 6 thereby providing superimposed strata for water treatment, which strata are herein designated by the reference characters 7 to 12 both inclusive. The water

coming from the inlet 3 is first received on the uppermost tray from which it passes through the stratum 7 to the next following tray. It then passes progressively through the strata 8 to 12 until it reaches the storage 70 space 14. Located in this storage space is a float 15 having operating connections 16 to a valve 17 in the inlet 3, whereby the rate of admission of water to the apparatus is controlled by the rate of withdrawal of deaerated water from the outlet 4. 75

In the operation of the apparatus thus far described, steam from the inlet 5 will have a tendency to flow into the various strata in the direction indicated by the arrows 18. In the absence of special provision of the character contemplated by the present invention, the steam flow into the upper stratum would be relatively greater than the steam flow into the lower stratum, and the lower stratum, for reasons pointed out, would tend to become partially or completely stagnated. In accordance with the present invention I provide the respective strata with baffling or flow controlling means 19 so disposed as to give venting areas 20 to 25 both inclusive of progressively increasing cross sectional area from the uppermost to the lowermost stratum. Thus, the stratum 12 is characterized by a venting area 25 which is materially greater than the venting area 20 for the stratum 7. 85

90 Cooperating with the apparatus is a vent condenser 26 the vapor space of which is open to the interior of the container through a connection 27. While this vent condenser may be of any one of a number of different types, I have herein illustrated it as comprising a single pass condenser receiving water in the header 28 through a suitable connection 29. The water travels from the header 28 to a discharge header 30 through tubes 31, and during such travel absorbs a large part of the heat of the vapors and gases passing through the connection 27. The condenser may be provided with a vent 32 discharging directly into the atmosphere or into an ejector, depending upon the temperature conditions which it is desired to maintain in the apparatus itself. 95

100 In abstracting heat from the vapor mixture, the vapors are condensed in the condenser, thereby decreasing their volume and tending to create a vacuum, which tendency is effective through the connection 27 for withdrawing further vapors into the condenser. The condenser thus constitutes a withdrawal means cooperating with the container 2. The effectiveness of the withdrawal means on the respective strata is determined by the size of the vent areas 20 to 25, both inclusive. It will thus be obvious that the vent condenser has the ability to exert a greater pull on the stratum 12 than it has on the stratum 7, the effectiveness of the pull increasing progressively in the direction of water flow. 105

In Figure 1 this condition is diagrammatically illustrated. In the curve of this figure the ordinates represent ease of venting or venting capacity having reference to the 5 quantity or area, while the abscissa represent the direction of water flow, having reference to the different stratum of treatment. For purposes of ready comparison the ordinates are designated by the reference characters 20' 10 to 25' corresponding to the vent areas 20 to 25, while the abscissa are designated by the references 7' to 12', having reference to the stratum themselves. The representative 15 curve C indicates diagrammatically the variation in the effectiveness of venting in the direction of water flow and illustrates clearly a maximum effectiveness progressively on the strata in the direction of water flow.

In Figure 2 there is illustrated diagrammatically the relationship between air quantities, temperature rise and natural tendency 20 toward steam flow as compared to the direction of water flow. In this figure the ordinates represent air quantity removed as a percentage 25 of the total air available, or temperature rise from the initial temperature of admission or percentage volume of initial flow of heating steam, while the abscissa represent direction of water flow and are designated similarly to Figure 1. The ordinates on the contrary are designated 7a to 12a, both inclusive. The resulting curve C indicates temperature rise of the water. By reference 30 to this curve it will be seen that the water 35 travelling through the stratum 7' would naturally induce a maximum percentage quantity represented by the amount 7a of the initial flow of the heating steam, while the water flowing through the successive zones or strata 40 8' to 12' would normally induce progressively smaller percentages of initial steam flow, designated as 8a to 12a inclusive.

The values 7a to 12a also represent the air 45 quantities released, the air quantities gradually decreasing under normal conditions as the water is successively treated until the removal curve becomes substantially parallel to steam quantity. The curve is thus ordinarily referred to as asymptotic and illustrates the difficulty under natural conditions 50 of operation of effecting complete air removal. In accordance with applicant's invention the air quantity 12a is removed with a quantity of steam represented by the ordinate 55 25' of Figure 1, which is a maximum steam flow from the stratum, while the air quantity 7a is removed by a minimum steam quantity from the stratum designated by the ordinate 20' of Figure 1. The maximum steam flow 60 from the stratum for the minimum air content insures the continuous maintenance of a substantially pure steam atmosphere in which pressure equilibrium may be advantageously accomplished.

65 In Figure 4, I have illustrated a slightly

modified embodiment of the invention in which parts corresponding to the parts heretofore described are designated by the same reference, having in each instance a value of 100 added thereto. In this embodiment the successive strata 107 to 112, both inclusive, 70 are formed by trays 106. The outlet from the stratum 107 is blocked by a baffle 119 of maximum size, thus affording a vent area 120 of minimum size. The size of the baffles 119 75 is progressively decreased in the direction of water flow, thereby providing withdrawal areas 120 to 125 both inclusive of progressively increasing size, whereby the maximum venting capacity is obtained in connection 80 with the last stratum 112. In this apparatus the conditions of operation will be contrary to conditions of normal operation in an open heater of the tray type, for example, and such as to induce a withdrawal effect which is greatest in the zone of least temperature rise and smallest in the zone of maximum temperature rise. The result is to always maintain steam atmospheres such as to facilitate 85 pressure equilibrium and air removal by maintaining the purest atmosphere in contact with the water having the least air content and subjected to the smallest temperature rise.

90 While I have herein illustrated and described strata or zones of treatment of the type formed by superimposed trays, it will be understood that such zones or strata may be otherwise formed and that the isolation or separation of the respective zones or strata 100 may be modified or changed in accordance with the particular design of the apparatus.

I claim:

1. In the method of deaerating, the steps 105 comprising passing the water to be deaerated through a heat exchanger, progressively subjecting the water to the action of steam in successive strata, continuously separately withdrawing steam and released air from such strata, and subjecting the strata having the least temperature rise to an increased withdrawal effectiveness.

2. In the method of deaerating, the steps 110 comprising passing the water to be deaerated through a heat exchanger, progressively subjecting the water to the action of steam in successive strata for raising the temperature thereof, continuously directly withdrawing steam and released air from such strata, and subjecting the strata having the least temperature rise to an increased withdrawal effectiveness.

3. In the method of deaerating, the steps 115 comprising passing the water to be deaerated 120 through a heat exchanger, progressively subjecting the water to the action of steam in successive strata, continuously separately withdrawing steam and released air from such strata, and progressively increasing the 125 130

withdrawal effectiveness on the strata as the temperature rise decreases.

4. In the method of deaerating, the steps comprising passing the water to be deaerated through a heat exchanger, progressively subjecting the water to the action of steam in successive strata for progressively increasing the temperature thereof, continuously directly withdrawing steam and released air from each of the strata, and progressively increasing the effective withdrawal action on the strata in the direction of water flow.

5. In the method of deaerating, the steps comprising passing the water to be deaerated through a heating apparatus, progressively subjecting the water to the action of steam in successive strata, continuously separately withdrawing steam and released air from all of the strata to a common point, and subjecting the stratum having the least temperature rise to the most effective withdrawal.

6. In the method of deaerating, the steps comprising passing the water to be deaerated through a heating apparatus, progressively subjecting the water to the action of steam in successive strata in said heat exchanger, continuously separately withdrawing steam and released air from each stratum, combining the steam and air at a common point, and subjecting the stratum having the least temperature rise to the most effective withdrawal.

7. In the method of deaerating, the steps comprising passing the water to be deaerated through a heat exchanger, progressively subjecting the water to the action of steam in successive strata, controlling the steam flow through such strata in such manner as to produce a gradually increasing pull through the strata in the direction of water flow, and withdrawing the released air from the heat exchanger.

8. In the method of deaerating, the steps comprising passing the water to be deaerated through a heat exchanger, progressively subjecting the water to the action of steam in a plurality of substantially horizontally extending superimposed strata, and controlling the steam flow through such strata to give a progressively increasing steam pull through the strata in the direction of the water flow.

9. In the method of deaerating, the steps comprising passing the water to be deaerated through a heat exchanger, progressively subjecting the water to the action of steam in successive strata, and progressively increasing the venting of the strata in the direction of water flow therethrough.

10. In a deaerator, a container, a plurality of trays therein forming superimposed water treating strata, and individual vents for said strata of progressively increasing size in the direction of water flow therethrough.

11. In a deaerator, a container, a plurality of trays therein forming superimposed wa-

ter treating strata, individual vents for said strata of progressively increasing size in the direction of water flow therethrough, and common means operative on all of said vents for inducing a steam flow through the various strata. 70

12. In a deaerator, a container, a plurality of trays therein forming superimposed water treating strata, individual vents for said strata of progressively increasing size in the direction of water flow therethrough, and flow inducing means cooperating with said vents. 75

13. In a deaerator, a container having a mixture outlet and a water inlet, a vent condenser having its vapor space operatively connected to said outlet and having its tube space connected to said inlet, means for controlling the flow of water through said condenser and inlet, a plurality of trays within said container, and means cooperating with said trays for insuring variable steam flow between different trays, said last mentioned means comprising a plurality of baffles forming vent openings for the inter tray spaces progressively increasing in area in the direction of water flow. 80 85 90

In testimony whereof I have hereunto set my hand.

JOHN R. McDERMET.
